United States Patent Office

Des. 222,432
Patented Oct. 26, 1971

222,432

WEDGE ANCHOR

Bruce L. Kaufman, Michigan City, Ind., assignor to
Phillips Drill Company, Inc., Indianapolis, Ind.

Filed July 20, 1970, Ser. No. 24,029

Term of patent 14 years

Int. Cl. D8—10
U.S. Cl. D8—272

FIG. 1

FIG. 2

FIG. 4

FIG. 3

FIG. 1 is a side elevational view of a wedge anchor illustrating my new design;

FIG. 2 is a fragmentary elevational view of the anchor of FIG. 1 showing the opposite side thereof.

FIG. 3 is a bottom end view of the anchor; and

FIG. 4 is a top end view of the anchor.

I claim:

The ornamental design for a wedge anchor, as shown.
